UNITED STATES PATENT OFFICE.

PETER GILLIS, OF BOSTON, MASSACHUSETTS.

WINDOW-FASTENER.

SPECIFICATION forming part of Letters Patent No. 341,745, dated May 11, 1886.

Application filed August 21, 1885. Serial No. 174,862. (Model.)

To all whom it may concern:

Be it known that I, PETER GILLIS, a citizen of the United States, residing at Boston, in the county of Suffolk and State of Massachusetts, have invented certain new and useful Improvements in Fastenings for Windows; and I do hereby declare that the following is a full, clear, and exact description of the invention, which will enable others skilled in the art to which it appertains to make and use the same.

My invention has for its object an automatic window-sash fastener, which will also serve to hold the two parts of the window firmly, so as to prevent the motion of the same, commonly called "rattling."

In the drawings I have shown in Figure 1 a perspective view of my invention, looking from without; in Fig. 2 a plan view of my invention; in Fig. 3 a sectional view of the same on the line *xx*, Fig. 2; and in Fig. 4 a sectional view of the same on the line *yy*, Fig. 2.

a is the part of my fastener to be attached to the upper window-sash, and *b* the part to be attached to the lower sash. The part *a* has the catch *c*, moving on the pin *f* in the slot *d* in the raised part *e*. The upper part of the catch *c* is bent in the manner shown in Fig. 2, so that it can easily be turned down by the thumb when the window is to be opened. This catch fits into the part *e* for the purpose of fastening the sashes.

h is a wedge-shaped piece attached to the forward part of *a*, or forming one piece with it, and fitting into a wedge-shaped slot, *i*, in the part *b*, as shown in Fig. 4. The forward end of part *e* fits into the recess *k* in the part *b*, which recess is of such shape as to permit

the forward end of part *e* to tightly fit therein, so as to allow no sidewise motion of the sashes upon each other, the upper part of the part *b* projecting beyond the front side of the sash to which it is attached, as shown in Fig. 4. It will be seen that when the window is closed the catch acts automatically and securely fastens the window, while the wedge-shaped piece *h* fits into the corresponding slot, *i*, and prevents all motion of the window in or out, and the part *e*, fitting into the recess *k*, prevents all sidewise motion of the sashes. When the window is to be opened, the catch *c* is to be turned down by the hand. It is obvious that it will be impossible to open this window from the outside by the insertion of a knife or similar instrument between the sash, or in any way except by breaking the glass, so as to turn the catch down, while at the same time the motion or rattling of the window is effectually prevented.

What I claim, and desire to secure by Letters Patent, is—

The automatic window-sash fastener, consisting of the parts *a* and *b*, to be attached, respectively, to the two parts of the window-sash, the part *a* having the wedge-shaped piece *h*, adapted to fit into a corresponding slot, *i*, in the part *b*, and the forward end of the part *a* adapted to fit into the recess *k* in the part *b*, and the catch *c*, moving in the slot *d* in the part *e* upon the pin *f*, substantially as and for the purpose above described.

PETER GILLIS.
